Primary Examiner — Jae Liang*(74) Attorney, Agent, or Firm* — Kenealy Vaidya LLP**CLAIM**

The ornamental design for a bottle including additive vessels, as shown and described.

DESCRIPTION

FIG. 1 is a front perspective view of a bottle including additive vessels showing the new design;

FIG. 2 is a bottom perspective view thereof;

FIG. 3 is a front view thereof;

FIG. 4 is a rear view thereof;

FIG. 5 is a right view thereof;

FIG. 6 is a left view thereof;

FIG. 7 is a top view thereof; and,

FIG. 8 is a bottom view thereof.

The broken lines in the drawings depict portions of the bottle that form no part of the claimed design.
